(57) **CLAIM**

The ornamental design for a tread of an automobile tire, as shown and described.

DESCRIPTION

FIG. 1 is a perspective view of a tread of an automobile tire; FIG. 2 is a front view thereof; FIG. 3 is a top view thereof; FIG. 4 is a right side view thereof; FIG. 5 is a fragmentary enlarged front view thereof; and, FIG. 6 is a section view taken along line 6-6 in FIG. 5. Broken lines in the drawings show portions of the tire that are not being claimed and thus form no part of the claimed design.
